UNITED STATES PATENT OFFICE.

ARTHUR H. EDDY, OF WINDSOR, CONNECTICUT, ASSIGNOR OF ONE-HALF TO
CHARLES E. SHEPARD, OF HARTFORD, CONNECTICUT.

EXPANSION-VALVE.

No. 853,503.

Specification of Letters Patent.

Patented May 14, 1907.

Application filed January 8, 1906. Serial No. 294,875.

To all whom it may concern:

Be it known that I, ARTHUR H. EDDY, a citizen of the United States, residing at Windsor, in the county of Hartford and State of Connecticut, have invented a new and useful Expansion-Valve, of which the following is a specification.

This invention relates to a valve which is particularly designed for use in a refrigerating system for controlling the flow according to the pressure of such a penetrating fluid as ammonia, although the valve which embodies this invention is applicable to other uses.

15 The object of this invention is to provide a comparatively simple, easily constructed valve for this purpose which will operate to control the flow of fluid according to the relative pressures on opposite sides of the valve 20 and also according to the temperature of the fluid which flows through the valve or temperature of a liquid which is affected by that fluid.

25 The accompanying drawing shows a central longitudinal section of a valve that embodies the invention.

The body 1 of the valve shown is preferably cast to shape with an end 2 for the attachment of the inlet pipe and an end 3 for the 30 attachment of the outlet pipe. In the body is a lining 4 fitting which is a plunger 5 which has a circumferential groove 6 near one end and passages 7 from the groove to the other end. At one end the plunger is connected 35 with a valve 8 which is adapted to shut against a seat 9. This valve and the plunger are fastened to a small diaphragm 10 that is held in the body by a plug 11. At the other end the plunger is fastened to a large diaphragm 12. When the valve is open fluid 40 flows from the inlet passage 13 past the valve and leaks by the plunger to the outlet passage 14. When the valve is closed no fluid can escape in this way. Thrusting 45 against the large diaphragm is a spring 15. The lower end of this spring is supported on a block 16 that is carried by the end of a toggle 17. The center of the toggle is connected by a link 18 with a double diaphragm 19 50 which by a pipe 20 is connected with a receptacle 21 that is designed to be placed in the liquid the temperature of which is to be utilized for influencing the flow of fluid through this valve. The lower end of the

toggle is adapted to thrust against an adjusting screw 22 which may be turned to regulate the angularity of the toggle and consequently the initial tension of the spring that thrusts against the large diaphragm. The link which connects the diaphragm with the toggle may be provided with a threaded post 23 and a thumb nut 24 which may be adjusted to determine the bend of the toggle and amount of contraction of the double diaphragm. On the post and thrusting between the adjusting nut 26 and the frame 27 is a spring 28 which acts in conjunction with the double diaphragm, that is, it tends to counteract the tension of the spring 15, and thus render the double diaphragm more sensitive.

The receptacle 21 may contain any expandable substance which when warm will expand the diaphragm and straighten the toggle and when cooled will contract the diaphragm and bend the toggle. The tension of the spring thrusting against the large plunger diaphragm is determined by the angle of the toggle and the angle of the toggle is controlled by the state of the double diaphragm which is regulated by the temperature of the substance in the receptacle.

The construction of the valve is immaterial to this invention. The valve shown in the drawing in order to illustrate the invention, is one designed to control the flow of ammonia in refrigerating plants. When this valve and regulating device are used in a refrigerating plant for controlling the flow of ammonia, as the pressure on the outlet side 85 of the valve rises sufficiently to by exertion on the large diaphragm thrust back the spring and drawn down the plunger the valve is closed so that no more fluid can flow. When the pressure on the outlet side drops sufficiently the spring thrusting against the diaphragm lifts the plunger and valve so that fluid may flow from the inlet through the valve past the plunger to the outlet.

In a refrigerating plant it is not only desirable to regulate the flow of the fluid according to the relative pressures on the inlet and outlet sides of the expansion valve so that the device will act automatically, but it is also desirable as the temperature becomes 90 reduced to have the device operate with greater relative pressures between the inlet and outlet sides of the expansion valve. In

such a case the receptacle containing the expansible substance is placed in or near the brine tank which is cooled by the ammonia that flows through the expansion valve. As the brine cools the double diaphragm contracts and bends the toggle and consequently lessens the tension of the spring which acts to open the valve so that the valve will close under lower pressure on the expansion side. As the brine warms the fluid in the receptacle expands the double diaphragm and straightens the toggle so as to stiffen the spring and this operates to permit the flow of ammonia with less relative pressure between the inlet and outlet sides because the pressure on the expansion side under these circumstances must be higher than before to effect the closing of the valve. In practice the valve does not continually open and shut, the conditions automatically become stable according to the pressure and temperature but by the employment of this construction the expansion pressure drops as the temperature drops and consequently increases the efficiency of the apparatus.

The invention claimed is:—

1. A regulating device having a body with an inlet, an outlet and a valve seat, a valve adapted to open and close against the seat, a diaphragm connected with and adapted to close the valve, a spring arranged to open the valve, and a hollow thermostatic diaphragm connected with and arranged to control the tension of the spring according to the thermostatic condition of the diaphragm, substantially as specified.

2. A regulating device having a body with an inlet, an outlet, and a valve seat, a plunger located on the outlet side of the valve seat, a valve located on the inlet side of the valve seat and connected with the plunger, a diaphragm connected with the plunger on the outlet side of the valve seat, a spring thrusting against the diaphragm, and a dia-

phragm connected with the spring whereby the tension of the spring is regulated by the condition of the latter diaphragm, substantially as specified.

3. A regulating device having a body with an inlet, an outlet and a valve seat, a plunger located on the outlet side of the valve seat, a valve located on the inlet side of the valve seat and connected with the plunger, a diaphragm on the inlet side of the valve seat and connected with the valve, a diaphragm on the outlet side of the valve seat and connected with the plunger, a spring thrusting against the diaphragm on the outlet side of the valve seat, and an expansible diaphragm arranged to control the tension of said spring substantially as specified.

4. A regulating device having a body with an inlet and outlet and a valve seat, a valve movable toward and from the valve seat, a hollow thermostatic diaphragm, and a spring thrusting between the valve and the thermostatic diaphragm and tending to lift the valve from its seat and having its tension varied according to the state of the said diaphragm, substantially as specified.

5. A regulating device having a body with an inlet, an outlet and a valve seat, a valve movable toward and from the valve seat, a spring arranged to thrust the valve from the valve seat, a toggle supporting the spring, and a thermostatic diaphragm adapted to actuate the toggle, substantially as specified.

6. In combination with a valve, a diaphragm arranged to move the valve in one direction, a spring arranged to move the valve in the opposite direction, and a hollow thermostatic diaphragm connected with and arranged to control the tension of the spring, substantially as specified.
